United States Patent

Des. 240,770

Patented Aug. 3, 1976

240,770

ANIMAL BISCUIT OR THE LIKE

Harold S. French, 60 E. 8th St.,
New York, N.Y. 10003

Filed Mar. 10, 1975, Ser. No. 556,647

Term of patent 7 years

Int. Cl. D1—01

U.S. Cl. D1—27

FIG. 1

FIG. 2

FIG. 1 is a top perspective view of an animal biscuit or the like showing my new design; and

FIG. 2 is a side elevational view thereof.

The bottom of the design is flat and unornamented.

I claim:

The ornamental design for an animal biscuit or the like, as shown and described.
